UNITED STATES PATENT OFFICE.

ERNEST R. CHATTERLEY, OF FLANDREAU, SOUTH DAKOTA.

FEED-BAG FASTENER.

Application filed September 25, 1922. Serial No. 590,557.

To all whom it may concern:

Be it known that I, ERNEST R. CHATTERLEY, a citizen of the United States, residing at Flandreau, in the county of Moody and 5 State of South Dakota, have invented certain new and useful Improvements in Feed-Bag Fasteners, of which the following is a specification.

This invention relates to certain new and 10 useful improvements in feed bag fasteners, and the primary object of the invention is to provide a fastener which is carried by the bridle of the harness and which not only holds the bag securely onto the head of the 15 horse, but which also renders it impossible for the horse to cause the fastener to be caught in his own harness or that of another thereby eliminating the source of runaways due to this cause with use of fasteners 20 of the type commonly employed.

The invention further aims to provide a fastener which can be economically produced and one which is devoid of all moving parts or ones which can be caught in the 25 harness or otherwise.

The invention also aims to provide a fastener which can be easily and quickly manipulated in attaching and detaching the bag.

30 The invention has still further and other objects which will be later set forth and manifested in the course of the following description.

In the drawings:—

35 Figure 1, is a front elevation of the invention;

Figure 2, is a side elevation, and

Figure 3, is a top plan view.

In proceeding in accordance with the

40 present invention, the fastener embodies a horizontal top bar 1, having integral inwardly extending end parts 2, the whole forming an outwardly extending U-shaped member or loop as illustrated in Figure 3.

45 The parts 2 are extended downwardly at 4 and then horizontally at 5, crossing each other at 6 and are then again extended downwardly at 7 and inwardly to lie in juxtaposition and are finally extended upwardly in parallelism as indicated at 8.

50 The parallel parts 8 are spaced apart and intermediate in outwardly inclined free terminals 9, the latter being disposed in approximate vertical alinement with the top bar 1.

In use of the invention, one of the fas-

teners is secured to each of the side straps of the bridle by the top bar 1, and the holding or supporting strap of the feed bag is held by the parts 8, 8 which latter provide 60 a somewhat hook-like formation the feed bag strap being threaded over the inclined ends 9, 9 and under the top bar 1, and since the ends 9, 9 are in register with the top bar, it will be seen that the latter protects same 65 and thereby prevents catching of the ends 9, 9 in the harness or otherwise.

The fastener may be formed of wire or may be stamped out of sheet metal and shaped to the form depicted in the drawings. 70

What is claimed is:—

1. In a feed bag fastener, a member having a substantially U-shaped horizontal top part provided with depending portions which latter are extended inwardly and 75 horizontally and cross each other and are then extended downwardly and contracted and finally extend vertically and upwardly and have outwardly inclined terminals which latter are in approximate register 80 with the outer member of the U-shaped top part.

2. In a feed bag fastener, a wire member formed intermediate its ends with a horizontal top part and with depending side portions which latter are extended inwardly in intersecting relation and then extended 85 downwardly and upwardly to form hooks, the free ends of the wire underlying the horizontal top part so as to be protected 90 thereby.

3. In a feed bag fastener, a body having a forwardly extending U-shaped loop open at its rear and located adjacent to the upper end of the body, a transverse supporting member for the body located below the loop, and a hook extending upwardly from the lower end of the body and extending across the transverse member and terminating below the loop and in approximate register 95 therewith so as to be protected thereby.

4. In a feed bag fastener, a wire member having a horizontal loop at its upper end, sides connected to the loop, a transverse supporting member located below the loop and connected to the sides and a hook like part connected to the sides and extending upwardly from the lower end of the body, and across said transverse part and terminating below the loop and in substantial register 105 therewith so as to be protected thereby.

5. In a feed bag fastener, a body having

a horizontally disposed protecting loop projecting therefrom, means to support the body from a part of the harness, and feed bag supporting means carried by the body and underlying the loop, the loop extending forwardly beyond said supporting means and beyond the sides of the latter to pre-

vent said means from catching in the harness of the wearer or the harness of an adjacent horse.

10

In testimony whereof, I affix my signature.

ERNEST R. CHATTERLEY.
